UNITED STATES PATENT OFFICE.

JOSEPH B. ST. ANDRE, OF BAYFIELD, WISCONSIN, ASSIGNEE OF ONE-FOURTH TO JOHN J. GUELFF AND W. C. HARRINGTON, BOTH OF MARQUETTE, MICHIGAN.

CLOTH CUTTING AND MEASURING MACHINE.

1,330,453.

Specification of Letters Patent. Patented Feb. 10, 1920.

Application filed July 3, 1917. Serial No. 178,463.

To all whom it may concern:

Be it known that I, JOSEPH B. ST. ANDRE, a citizen of the United States, residing at Bayfield, in the county of Bayfield and

5 State of Wisconsin, have invented certain new and useful Improvements in Cloth Cutting and Measuring Machines, of which the following is a specification.

This invention relates to a device for 10 measuring and cutting cloth, ribbons or cordage.

The object of the invention is to facilitate the running off of a desired length, the mechanism being set for a predetermined 15 length and the feed device automatically coming to a stop when the desired amount has passed through the feed rollers.

The cutting device is arranged so that 20 the piece will be cut at exactly the right point to give the length measured out.

The invention consists in the novel features of construction hereinafter described, pointed out in the claims, and shown in the 15 accompanying drawings, in which—

25 Figure 1 is a sectional elevation of the device.

Fig. 2 is a plan view, the cover being removed.

Fig. 3 is an end view of a housing and 30 dial, a shaft and the base being in section.

Fig. 4 is a section on the line 4—4 of Fig. 1, a pawl and a ratchet wheel being shown in elevation.

Fig. 5 is a section on the line 5—5 of 35 Fig. 2.

In constructing the device I employ a suitable base 1 partially covered by a housing 2. In said housing and extending from one end of it is a shaft 3. The outer end 40 portion of the shaft carries a feed roller 4, and a bracket 5 adjustably supports a tension roller 6. Tension is applied by means of a spring pressed yoke 7 the handle 8 of which works through the top of the bracket 5 and said handle is provided with a collar 9, and a pivoted latch 10 carried by the top of the bracket is adapted to be swung into position against the handle and below the collar, thereby holding the yoke 45 and the roller 6 elevated. The bracket 5 is vertically slotted to allow for vertical movement of the shaft of the roller 6. The end of the housing 2 adjacent the bracket 5 has a slot 11 forming almost a complete circle

cut therein. A spring 12 is placed about 55 the handle 8 and between the bracket and the yoke and applies downward pressure thereon.

Opposite the rollers above described and secured to the base 1 is a bracket 13 carrying a horizontal knife 14 normally protected by a hinged guard or cover 15.

Within the circle formed by the slot 11 is placed or painted a dial indicating by suitable numerals or characters various 60 lengths or distances, which may be expressed in inches, feet or yards, according to the kind of goods to be measured, and there is of course a certain proportion maintained between the diameter of the roller 4, the 65 diameter of the dial, and scale laid off thereon.

Arranged in the housing there are in addition to the shaft 3 shafts 16, 17, the latter being journaled in the center of the 70 dial and having fixed thereto a hand 17^a that travels over the dial.

On the shaft 3 is a pinion 18 meshing with a gear 19 on the shaft 16. This shaft carries a pinion 20 meshing with a gear 80 21 on the shaft 17. All of these parts are so proportioned that when one inch, or one yard, or one foot, or whatever may be the unit of measure, of cloth or ribbon or rope has passed between the rollers, the 85 hand 17^a will have traveled over a corresponding marked distance on the dial. It will be noted that the knife is some distance from the rollers and this distance is taken into account in measuring the goods. 90

A ratchet wheel 22 is fixed on the shaft 17 and is normally engaged by a pawl, spring pressed; 23. A coil spring 24 is connected to the shaft 17 and returns the parts mentioned including the hand 17^a to normal 95 position upon disengagement of the pawl. As the pawl projects through the cover or top of the housing it is within easy reach of the clerk and the pressure of the thumb on the pawl resets the device. 100

To stop the hand 17^a and the parts connected thereto, including the feed roller, I place a sleeve 25 loosely on the shaft 17 where it passes through the dial center, and secure to the sleeve a bracket arm 26 which 105 works in the slot 11, and I also connect to the sleeve a hand 27 which travels over the dial. A pin 27 pressed by spring 28 is car-

ried by the bracket arm 26 and this pin is adapted to engage openings 30 distributed around the dial for locking the arm 26 in place.

5 The method of operating the device is as follows:

The bracket arm 26 is properly placed, the latch 10 swung back to allow the upper roller to bear on the lower feed roller 4, 10 the rollers having rubber surfaces, and the knife guard 15 raised. It will be noted that the cutting blade is positioned between two pieces of wood 14^a with the back edge of the blade visible from above. This edge 15 forms a straight line and the material to be cut is drawn through the rollers and to this line, the measuring operation being then started. When the desired amount of material has been drawn between the rollers it 20 is pulled upwardly against the knife 14 and then drawn along or parallel to the edge of the knife, and thus severed. When the material is cut the remainder will be left in proper position for the measuring of subsequent portions.

25 A groove 4^a is formed on the roller 4 to allow for the measuring of cordage. Elastics can be measured by making proper provision for their stretching.

30 Provision may also be made for locking the guard in closed position over the knife if desired.

35 It will be noted that the hand 17^a is not directly engaged by the stop arm 26. An arm 17^b is secured on the shaft 17, within the casing, and engages a lug 26^a on the stop arm 26.

What I claim is:

1. In a device of the kind described, a 40 housing having a dial on one end and partially slotted about said dial, an exterior set of feed rollers, a shaft extending through the housing and carrying one of said rollers, a second shaft carried by the housing and centrally located with respect to the dial, 45 interior and exterior hands fastened to said shaft, the exterior hand traveling over the dial, a bracket arm movable about the shaft and dial, means for locking said arm, the interior hand engaging said arm when the first mentioned shaft has made a predetermined number of rotations, and means for transmitting rotation from the roller shaft to the second mentioned shaft.

2. A device of the kind described comprising a set of rollers, a housing, a shaft 55 extending from the housing and carrying one of the rollers, a dial on the end of the housing adjacent the rollers, the housing being slotted, the slot extending almost 60 around the dial, a second shaft extending through the dial center, hands thereon, one of the hands traveling over the dial and the other being within the housing, an angled arm movable about said second shaft and 65 extending through the slot of the dial, means for locking the arm against movement, and in position to be struck by the interior hand, gearing adapted to transmit motion from one shaft to the other, and 70 means for returning the two hands to normal or zero position.

In testimony whereof I affix my signature.
JOSEPH B. ST. ANDRE.
